United States Patent Office

Des. 197,681
Patented Mar. 10, 1964

197,681

DOOR BELL

Norman William Stevenson, Macclesfield, England,
assignor to V. & E. Friedland Limited, Macclesfield,
England, a British company

Filed Mar. 12, 1962, Ser. No. 69,216

Claims priority, application Great Britain Sept. 13, 1961

Term of patent 14 years

(Cl. D72—1)

FIG. 1 is a front elevational view of a door bell embodying the design of the present invention;

FIG. 2 is a rear perspective view;

FIG. 3 is a fragmentary vertical section taken on the line 3—3 of FIG. 1;

FIG. 4 is a side elevational view and

FIG. 5 is a top plan view.

The dominant features of my design reside in the portions shown in full lines.

I claim:

The ornamental design for a door bell, as shown and described.
